James Sutton Carmlee
his ATTORNEY

UNITED STATES PATENT OFFICE.

PAUL WERNER SEEWER, OF LONDON, ENGLAND, ASSIGNOR TO THE ENGLISH ELECTRIC COMPANY LIMITED, OF LONDON, ENGLAND, A BRITISH COMPANY.

HYDRAULICALLY-ACTUATED DEVICE.

Application filed August 12, 1924, Serial No. 731,654, and in Great Britain December 22, 1923.

This invention relates to the control of hydraulically actuated devices and provides for the carrying out of this control by means of a regulating valve influencing the flow of pressure fluid, the effect of which valve is varied progressively as the moving part of the device proceeds on its course. Control of this kind is desirable in cases where it is advantageous for the movement of the controlled part to be much more rapid at one stage of its movement than at another; for instance, in the case of the main valve for the supply to an hydraulic turbine the closing movement should be relatively rapid in the early and middle stages and should gradually be retarded as the completion of the closure is approached. Conversely, during the opening the movement should be slow at first and then more rapid.

In hydraulically actuated devices to which the present invention relates there is employed a servo-motor in the form of a cylinder closed at both ends and having a piston working in it and passages for conducting pressure fluid into and exhausting it from the space within the cylinder on each side of the piston. A regulating valve is inserted in one of these passages being so arranged that the whole movement of pressure fluid into and out of the cylinder space with which it connects takes place through this valve. The valve comprises an adjustable regulating member and this member in accordance with the invention is operatively connected with the actuated part which itself is in operative connection with the piston of the servo-motor. The movement of the regulating member of the valve which takes place by reason of its operative connection with the actuated part effects the variation of the throttling effect of the regulating valve on the pressure fluid passing through it and thereby determines the speed at which the servo-motor moves. With this arrangement it is possible to obtain very great variation in speed of the actuated part at different points in its stroke.

The invention will now be described by way of example with reference to the accompanying drawings, Figure 1 of which shows in section a part of a main valve for controlling the supply of fluid to an hydraulic turbine together with a regulating valve having an adjusting member in the

form of a screw threaded spindle adapted gradually to retard the closing movement of the main valve according to the invention. Figure 2 is an enlarged sectional view of the regulating valve portion of Figure 1 and Figure 3 shows an enlarged detail view of the screw threaded spindle.

The outer circular wall of the valve is denoted by 1 and a two part central member by 2, each part being fixed by ribs to the outer parts of the valve. The ribs attached to the right hand part are denoted by 3 and are fixed to the tubular member 6. Water flows through the valve from left to right in Figure 1 and when it reaches the central member 2 it flows through the annular passage 4 formed by the members 1 and 2. The movable part of the valve by which the flow of fluid is regulated is the annular body 5 which is adapted to slide axially along the tubular member 6. The right hand extremity of the annular body 5 is thickened up and is provided with hydraulic washers so as to act as a double acting piston 11 within an annular cylinder having spaces 7 and 8 for the operating fluid. When space 7 is connected to a source of fluid under pressure and space 8 is connected to exhaust, the annular body 5 moves to the left and the closing action commences and is completed as soon as the end 9 of the body 5 reaches the ring 10 upon the central member 2. In a converse manner opening is effected by connecting the space 7 to exhaust and the space 8 to the source of pressure.

The adjusting member of the main valve 90 is a spindle 12 having on a part of its surface a screw thread 13 preferably of square section which works within cylinder 14 of such size that the top of threads 13 has just sufficient clearance therein to permit free movement without producing appreciable leakage. By varying the threaded length of spindle which lies in the cylinder the resistance to the passage of the fluid through the cylinder is adjusted. The cylinder 14 will, 100 in general, form part of a chamber within which the whole of the spindle is housed, and it will have apertures for the inflow and outflow of fluid at the two ends of the portion which is intended to include that part 105 of the spindle which is effective for regulating action. In this case cylinder 14 is arranged with one end discharging directly

into space 7. A reduced portion of spindle 12 extends through part of cylinder 14 and projecting therefrom is attached in suitable manner to the piston 11 of the annular body 5 so as to move therewith, bringing more or less of the threaded portion into the path of the pressure fluid as the movement of the piston 11 proceeds.

In the present instance cylinder 14 is 10 screwed into the end flange 15 of the main valve and its outer end is closed by cap 16 which screws onto the end of the cylinder and forms a housing for spindle 12. Spindle 12 is reduced or is joined to a part 15 of smaller cross section at its end adjacent to space 7 so that only a small length of its threaded portion rests within cylinder 14 when the annular body 5 is in its open position, as shown in the drawing. The pressure fluid enters cylinder 14 near its outer 20 end, by way of duct 17.

In order to produce a controlling action 25 of a particular kind or degree, the section of the restricted regulating passage may be varied simultaneously with the variation in its length. This may, for instance, be brought about by making the thread 13 on the spindle 12 of varying depth or width. Another kind of variation may be obtained 30 by varying the pitch of the thread 13, so that there is a varying number of threads per inch along the length of the threaded spindle. All these variations are clearly 35 shown in the large view of the spindle in Figure 3. In this figure the depth of the thread is a maximum at its extreme left hand, where a minimum amount of throttling of the fluid is required. The depth gradually decreases until it is a minimum at the 40 extreme right hand. It will also be observed that both the pitch and the width of the space of the thread are greater at the left hand than at the right hand. The thread 45 can either be cut directly upon the spindle or a number of collars, upon the outside of each of which some of the thread has been cut, may be slid upon the spindle and held in position by an end bolt.

Another type of change in the form of the 50 controlling action may be brought about by arranging that the regulating part of the spindle is not in action during the whole of the movement. This could be provided for in the drawings by removing thread 13 for 55 a certain distance on the left side of the threaded part of spindle 12 (for example up to the dotted line 19 in Figure 3) so that the water can flow freely through the duct 17 into the chamber 7 until the body 5 has advanced a definite distance sufficient to bring 60 the threaded part into the cylinder 14. The point in the stroke of the body 5 at which this takes place may be made adjustable by 65 an arrangement for producing relative displacement of the threaded part of the

spindle and the cylinder in addition to the displacement which occurs when the device is in action.

When it is desired to open the main valve 70 the pressure fluid is supplied to the duct 18 in Figure 1 and the duct 17 is connected to exhaust. The annular body 5 will then commence to move very slowly towards the open direction since the water can only escape to exhaust very slowly through the many threads which now lie in the cylinder 14 between the duct 17 and the space 7. As the opening movement continues and fewer threads are effective it will become more and 75 more rapid.

It will be recognized that other constructional modifications are possible one of which is to have the thread upon the inside of the cylinder 14 and to arrange that it co-acts with an unthreaded spindle of suitable diameters. Moreover the relative movement between the spindle and the cylinder could be provided by displacement of the latter instead of the former.

What I claim as my invention and desire 80 to secure by Letters Patent is:—

1. Hydraulic actuating means by which the speed of movement of the actuated part is made dependent upon its position comprising, in combination with the actuated parts, a servo-motor operatively connected therewith and being in the form of a cylinder closed at both ends and having a piston working therein and passages for conducting pressure fluid into and exhausting it 85 from the space on each side of the piston, a regulating valve inserted in one of said passages so that the whole movement of pressure fluid into and out of one of said spaces which accompanies the movement of the piston takes place through the said valve, a movable regulating member in the said valve, means operatively connecting the said regulating member with the actuated part so that they move simultaneously and means 90 adjusted by the said regulating member for varying the throttling effect of the said regulating valve on the pressure fluid passing 95 through it.

2. Hydraulic actuating means by which 100 the speed of movement of the actuated part is made dependent upon its position comprising, in combination with the actuated part, a servo-motor operatively connected therewith and being in the form of a cylinder closed at both ends and having a piston working therein and passages for conducting pressure fluid into and exhausting it 105 from the space on each side of the piston, a regulating valve inserted in one of said passages so that the whole movement of pressure fluid into and out of one of said spaces which accompanies the movement of the piston takes place through the said valve, a movable regulating member in the said 110

valve, means operatively connecting the said regulating member with the actuated part so that they move simultaneously and means adjusted by the said regulating member for varying the length of a restricted passage for the pressure fluid through the said regulating valve.

3. Hydraulic actuating means by which the speed of movement of the actuated part is made dependent upon its position comprising, in combination with the actuated part, a servo-motor operatively connected therewith and being in the form of a cylinder closed at both ends and having a piston working therein and passages for conducting pressure fluid into and exhausting it from the space on each side of the piston, a regulating valve inserted in one of said passages so that the whole movement of pressure fluid into and out of one of said spaces which accompanies the movement of the piston takes place through the said valve, a movable regulating member in the said valve, means operatively connecting the said regulating member with the actuated part so that they move simultaneously and means adjusted by the said regulating member for varying simultaneously the length and the cross section of a restricted passage for the pressure fluid through the said regulating valve.

4. Hydraulic actuating means by which the speed of movement of the actuated part is made dependent upon its position comprising, in combination with the actuated part, a servo-motor operatively connected therewith and being in the form of a cylinder closed at both ends and having a piston working therein and passages for conducting pressure fluid into and exhausting it from the space on each side of the piston, a regulating valve inserted in one of said passages so that the whole movement of pressure fluid into and out of one of said spaces which accompanies the movement of the piston takes place through the said valve, a movable regulating member in the said valve, means operatively connecting the said regulating member with the actuated part so that they move simultaneously and means adjusted by the said regulating member for varying the length of a restricted passage formed by means of a screw thread for the pressure fluid through the said regulating valve.

5. The combination in a valve of a passage for fluid, a movable valve member adapted to open and close said passage, a pressure-tight chamber external to said passage, a piston working in said chamber and operatively connected with said closing member, fluid-conducting means restricting the flow of pressure fluid at any instant to a single direction relative to the space between the said piston and one end of said chamber, a

regulating valve embodied in said conducting means so that the whole movement of pressure fluid into and out of the said space associated with the movement of the said piston takes place through the said regulating valve, a movable member in said regulating valve operatively connected with the said piston and effecting the adjustment of the length of a restricted passage through the said regulating valve so that this length increases as the piston moves in its chamber towards the position in which it produces the closing of the main valve.

6. The combination in a valve of a passage for fluid, a movable valve member adapted to open and close said passage, a pressure-tight chamber external to said passage, a piston working in said chamber and operatively connected with said closing member, fluid-conducting means restricting the flow of pressure fluid at any instant to a single direction relative to the space between the said piston and one end of said chamber, a regulating valve embodied in said conducting means so that the whole movement of pressure fluid into and out of the said space associated with the movement of the said piston takes place through the said regulating valve, a movable member in said regulating valve operatively connected with the said piston and effecting the adjustment of the length of a restricted passage, formed by means of a screw thread, through the said regulating valve so that the active length of the screw thread increases as the piston moves in its chamber towards the position in which it produces the closing of the main valve.

7. The combination in a valve of a passage for fluid, a pressure-tight chamber, a member working in said chamber and extending by way of a pressure-tight aperture to the outside of said chamber and into said passage, the said member having its end within the chamber enlarged to form a piston and having that part of it which extends outside the chamber adapted to serve as a closing member for the passage, fluid conducting means restricting the flow of pressure fluid at any instant to a single direction relative to the space between the said piston and one end of said chamber, a regulating valve embodied in said conducting means so that the whole movement of pressure fluid into and out of the said space associated with the movement of the said piston takes place through the said regulating valve, a movable member in said regulating valve operatively connected with the said piston and effecting the adjustment of the length of a restricted passage through the said regulating valve so that this length increases as the piston moves in its chamber towards the position in which it produces the closing of the main valve.

8. The combination in a valve of a passage

for fluid, a pressure-tight chamber, a member working in said chamber and extending by way of a pressure-tight aperture to the outside of said chamber and into said passage, the said member having its end within the chamber enlarged to form a piston and having that part of it which extends outside the chamber adapted to serve as a closing member for the passage, fluid conducting means restricting the flow of pressure fluid at any instant to a single direction relative to the space between the said piston and one end of said chamber, a regulating valve embodied in said conducting means so that the whole movement of pressure fluid into and

out of the said space associated with the movement of the said piston takes place through the said regulating valve, a movable member in said regulating valve operatively connected with the said piston and effecting the adjustment of the length of a restricted passage, formed by means of a screw thread, through the said regulating valve so that the active length of the screw thread increases as the piston moves in its chamber towards the position in which it produces the closing of the main valve. 20 25

In testimony whereof I affix my signature.
